SHUTTLE MECHANISM FOR LOOMS

Benjamin Liebowitz, Lewisboro, N. Y.

Application August 7, 1946, Serial No. 688,817

25 Claims. (Cl. 139—142)

1

This invention relates to looms and in particular to shuttle mechanism for looms including the loom shuttle and means for propelling the loom shuttle.

The principal objectives of this invention are to effect a substantial increase in speed, to reduce power consumption, to minimize shock at each acceleration and deceleration of the shuttle, and to gain other advantages as will hereinafter appear.

In conventional designs of looms, the speed, i. e., the number of picks per minute, is severely limited by the weight of the shuttle. Moreover, the size of the shuttle and other elements in the design and operation of the associated mechanism make it necessary to use large and jerky motions of the heddles, which motions impose severe stresses on the warp threads and hence also constitute a restriction on the speed at which such looms can be operated.

Attempts hitherto made to overcome these difficulties by reducing the size of the shuttle have not been successful because shorter and lighter shuttles tend to be erratic in their flight; i. e., lighter shuttles show a lack of stability in their motion, and so have had to be abandoned. Current tendency in textile design is, in fact, in the opposite direction; that is, the tendency now is to reduce handling by increasing of "package" size, including under the term "package" the amount of cotton on the shuttle bobbin. This involves an increase in the size and weight of the shuttle, rather than a decrease.

According to this invention, the problem of reducing the size and weight of a loom shuttle is met by stabilizing the shuttle in its flight by means of gyro mechanism. The stabilizing effects of gyro mechanisms are well known and need not be discussed herein. The inclusion of one or more gyro mechanisms in a loom shuttle constitutes one of the main features of this invention.

When a gyro mechanism is included in a loom shuttle, the rotatable inertia member or gyro can be driven in any suitable way. Thus, the gyro can be driven by impulsion at the end of each pick or each alternate pick during the operation of the shuttle mechanism of the loom. For example, there may be associated with the flywheel or gyro of the gyro mechanism small buckets or other deflectors and means may be provided for directing a jet of compressed air against these buckets or deflectors to cause rapid rotation of the gyro. In such case, the jet of compressed air may be directed against the deflectors to rotate the gyro at the end of each

2

pick or each alternate pick, for example, when the shuttle is in the shuttle box. For this purpose, aperture means may be provided in a casting member of the loom shuttle which is disposed about the gyro mechanism and aperture means may also be provided in either or both of the shuttle boxes used for receiving the shuttle at the end of each pick, and these aperture means may be arranged so that a jet of air can be directed therethrough from a suitable source of compressed air for impinging upon the deflectors. Alternatively, electromagnetic means may be provided for rotating the gyro of the gyro mechanism in the loom shuttle. For example, the gyro may be the armature of an electric motor and means may be provided for supplying suitable voltage to the electric motor with the aid of contacts that are made at the end of each stroke or alternate stroke of the shuttle so as to supply electric power for actuating the electric motor and effect rapid rotation of the gyro. In such case, the field of the motor can either be in the shuttle box or in the shuttle itself. Another electromagnetic means that may be employed consists in making the gyro in the form of a rotor in an induction motor and by providing stator means, namely, means for producing a rotating magnetic field, at the shuttle box at the end of each stroke or alternate stroke of the shuttle. Moreover, impulsion for effecting rotation of the gyro may be supplied by mechanical means contained entirely within the shuttle by utilizing inertia forces arising from acceleration and/or deceleration of the shuttle to effect longitudinal movement of the gyro relative to the shuttle, which longitudinal movement can be caused to impart spin to the gyro by suitable means such as a screw or helix on the shaft on which the gyro is mounted and by employment of a ratchet device or the like for permitting reverse movements. More generally, any appropriate means may be used in the practice of this invention for supplying power for impulsion of the gyro of the gyro mechanism in the loom shuttle so that the gyro will rotate rapidly during the flight of the shuttle and thereby stabilize the shuttle in its flight. By thus stabilizing the shuttle in its flight, the weight of the shuttle can be made much less than shuttle weight previously required in order to prevent erratic flight of the shuttle.

The size of a loom shuttle must depend to a considerable extent upon the amount of cotton or other thread on the bobbin or cop which is carried by the shuttle. However, in view of the well-

known mechanisms such as those in common use for automatically changing bobbins when they approach emptiness, no serious disadvantage is necessarily incurred in reducing the amount of thread carried by the shuttle bobbin or cop, to a minimum. For example, the amount of cotton carried by a fresh bobbin may be sufficient for a few hundred picks, which is a small number compared with current practice. However, the disadvantage incurred, because the bobbin-changing mechanism must operate more frequently is trivial. A more serious disadvantage would be incurred, however, by the wastage which would ordinarily result if the length of weft yarn lost at each change of the bobbin were the same as in current practice. This disadvantage can be overcome, however, by winding a predetermined length of weft yarn on the bobbin or cop and automatically changing the bobbin or cop after a predetermined number of picks, that is, a number just sufficient to use up the predetermined length of yarn with allowances for variation in the "crimp," etc.

By employment of gyro mechanism in the loom shuttle for stabilizing the shuttle in its flight and by reducing the amount of weft yarn on a fresh bobbin or cop to a practicable minimum, means are made available by this invention for substantially raising the speed limitations to which looms have hitherto been subject.

One of the many advantages gained by a substantial reduction in the size of the shuttle lies in the fact that the angular opening of the shed at the time of passage of the shuttle through it can be correspondingly reduced. This also permits reducing the stroke of the heddles and/or smoothing out their motions, thereby reducing the accelerations impressed on the warp yarns and hence raising the limitation on speed which would otherwise be imposed by these motions. These comments apply similarly to the beater mechanism.

It has been the practice in loom design for generations to guide the shuttle during its flight by means of a "running board" and "sley" carried by the beater mechanism. The function of the "running board" is to keep the shuttle from dropping in its flight, for without it the shuttle under ordinary conditions would drop considerably in the interval from the beginning to the end of its flight.

A loom shuttle comprising a gyro mechanism according to this invention can be used in connection with guiding means such as the "running board" and "sley". However, in order to reap the maximum benefit from the stability of the trajectory of the shuttle resulting from the use of the gyro mechanism, it is preferable according to this invention to propel the shuttle through the shed without supporting it or guiding it in any way. In other words, one of the advantages of the gyro shuttle lies in the fact that its trajectory can be made sufficiently stable so that it can make its traverse through the shed in free flight without any encumbrances other than aerodynamic forces, drag of the weft yarn, and so forth.

When a shuttle is propelled horizontally through the shed, it is under the influence of gravity, the amount of gravitational fall depending upon the duration of the unsupported flight of the shuttle. For example, a shuttle in free flight lasting $\frac{1}{25}$ second falls about 0.16 foot or 1.92 inches during its flight, whereas, if the flight lasts only $\frac{1}{25}$ second, the fall is only 0.307 inch. In

order that the shuttle may be reciprocated in free flight between oppositely disposed shuttle boxes, the gravitational fall of the shuttle can be compensated for in different ways, namely, (a) by disposing the shuttle box in a slightly inclined position with the shuttle receiving end upwardly so as to impart a compensating upward velocity to the shuttle and elevate its trajectory as in the firing of a rifle, or (b) by imparting an upward velocity to the shuttle box as a whole during propulsion of the shuttle and thereby impart a vertical component to the movement of the shuttle, or (c) by oscillating each shuttle box in such manner that its propelling position is vertically above its receiving position by the amount of fall. In the case of compensating means (b) and (c) above referred to, the longitudinal axis of the shuttle is horizontal as it is propelled from the shuttle box and during its flight. In the case of compensating means (a), the longitudinal axis of the shuttle is inclined as it is propelled from the shuttle box and during its flight. Each of the compensating means referred to above as (a), (b) and (c) may be used exclusively of the others, and, of course, can be used in any combination with each other.

A shuttle containing a gyro mechanism will tend to maintain its axial orientation in flight due to the stabilizing action of the gyro (except for such yaw or precession as may arise from various causes), and for this reason the longitudinal axis of the shuttle remains in substantially the same disposition during the flight of the shuttle. The compensating means referred to as (b) and (c) hereinabove have the advantage that the longitudinal axis of the shuttle remains horizontal during flight so that the shuttle can enter the bore of a horizontally-disposed shuttle box without incident impact required to align the longitudinal axis of the shuttle with the bore of the shuttle box as the shuttle enters the shuttle box. However, when the compensating means (a) is employed, the longitudinal axis of the shuttle is necessarily inclined during its flight and this results in misalignment of the longitudinal axis of the shuttle with the bore of the shuttle box which receives the shuttle at the end of its flight. This is somewhat disadvantageous if the misalignment is substantial, for, in order to align the shuttle axis with the bore of the shuttle box receiving the shuttle, a jarring impact is required due to rapidity of the flight of the shuttle.

The type of compensating means employed in order to compensate for the gravitational fall of the shuttle in free flight will depend upon the circumstances. By use of a lightweight shuttle and by employing the high speeds which are possible according to this invention, the disadvantages incident to compensating means (a) are small: Thus, if the time of flight is, for example, $\frac{1}{25}$ second and the length of free flight is, for example, 5 feet, the average horizontal velocity of the shuttle is 125 feet per second, its fall is 0.307 inch or 0.0256 foot, and its average falling velocity is, therefore, 0.64 foot per second, which is only 0.51% of the transverse velocity of the shuttle. This means that the angle of elevation of the bore of the shuttle box required to correct completely for the fall of the shuttle in its flight is only 0.0051 radian or about 0.29°. Accordingly, complete correction for fall of the shuttle under the conditions indicated can be obtained by pointing the bore of the shuttle box upwardly toward the shed at an angle of 0.29°. It follows that the misalignment between the longitudinal axis of

the shuttle and the axis of each of the shuttle boxes as the shuttle is received by each shuttle box is approximately twice 0.29°, or 0.58°. Such small error in alignment may be taken care of by suitable tapering or funneling of the mouth of the shuttle box. In this connection, it may be mentioned that some tapering or funneling of the mouth of the shuttle box is necessary in any case to provide for small errors in the propulsion of the shuttle from the oppositely-disposed shuttle box and to provide for yaw due to other causes such as aerodynamic forces, yarn drag, and movement set up during propulsion. If desired, the funnel-shaped part of the shuttle box may be lined, for example, with wood or leather, in order to minimize the shock which results from the slight amount of impact that results from the misalignment of the axis of the shuttle when it enters the shuttle box in case the compensating means referred to as (a) hereinabove is employed. In using compensating means (a), it may be desirable to correct for misalignment due to elevation of trajectory and non-horizontal disposition of the shuttle axis, especially when lower shuttle speeds or wider looms are used, thereby increasing the error. Such correction can be effected, for example, by oscillating the longitudinal axis of the shuttle box in a vertical plane about a horizontal transverse axis near its mouth so that the shuttle box points upwardly at the required angle during propulsion of the shuttle therefrom and downwardly at the required angle upon receiving the shuttle. Moreover, other means for correcting for fall and misalignment of the shuttle axis and shuttle box may be employed in conjunction with the compensating means (a) hereinabove referred to. For example, compensating means (a) may be combined with compensating means (c) by pivoting the shuttle box at some other point along its length instead of at or near the mouth so that when the shuttle box is oscillated about this axis the mouth will move vertically. In this combination of compensating means (a) and (c), the angle of elevation of the trajectory would be less than in pure (a), and the mouth of the receiving shuttle box would be lowered by the amount of resulting net fall.

As mentioned above, compensating means (b) and (c) have the advantage of maintaining the longitudinal axis of the shuttle horizontal except for yaw, etc. (so that impact with the shuttle box due to misalignment is minimized). However, there may still be impact due to difference in vertical velocity between the shuttle and the shuttle box it is entering. Further, there is a cause of residual impact due to the elongated shape of the shuttle, which I will refer to as "tail slap." Both of these causes of impact can be eliminated or minimized by employing the compensating means (b) whereby means is provided for causing vertical reciprocation of the shuttle boxes in proper phase with the shuttle-propelling means so that the receiving shuttle box at the moment of the initial contact of the shuttle therewith is moving vertically at essentially the same velocity as the vertical velocity of the shuttle. Moreover, by maintaining the vertical velocity of the shuttle box constant during the period of ejection and during period of reception of the shuttle, no disturbance of the longitudinal axis of the shuttle will occur during the period of ejection and during the period of reception. In this arrangement, then, there will be no tail slap except for the unavoidable pres-

ence of small amounts of yaw or precession. In contrast, compensating means (c) above, if used alone, involves both impacts now under discussion. Thus, if the shuttle is ejected from a stationary elevated position of the shuttle box and is received by the opposite shuttle box in a stationary lowered position, there will be an impact between shuttle and shuttle box due to the velocity of fall of the shuttle; moreover, the leading end of the shuttle will be arrested vertically before the trailing end, and this will result in some tail slap. According to one preferred embodiment of this invention, means is provided for causing vertical reciprocation of the shuttle boxes in combination with synchronizing means associated with the shuttle-propelling means whereby the shuttle box at the moment of initial contact of the shuttle therewith is moving downwardly at essentially the same velocity as the downward velocity of the shuttle due to gravitational fall. Another good method consists in imparting such vertical velocity to the shuttle during ejection that it reaches the opposite shuttle box at the highest point of its trajectory and is received by the shuttle box in a corresponding highest point of its motion while it is momentarily at rest. Here again the shuttle and receiving shuttle box have the same vertical velocity, viz., zero vertical velocity. This modification is still classified under compensating means (b).

In order to minimize the possible injury due to impacts when the shuttle enters the shuttle boxes, it is preferable to make the shuttle for use according to this invention so that the shuttle comprises an elongated body portion for containing the bobbin or cop and so that the shuttle comprises end portions having substantially greater cross-sectional area than the cross-sectional area of the body portion. These enlarged end portions are also advantageous for encasing the gyro mechanism which may be disposed in either or both ends of the shuttle.

One of the objects of this invention is to minimize vibration and impact forces arising from the acceleration and deceleration of the shuttle and also to reduce the power consumption for maintaining the reciprocatory flight of the shuttle between the shuttle boxes. According to this invention, novel shuttle propulsion means are employed comprising a movable shuttle-propelling member for propelling and receiving the shuttle and actuating means to accelerate and decelerate the shuttle-propelling member in each direction of its reciprocatory movement, the mechanism being such that, at the movement of initial receiving contact of the shuttle with the shuttle-propelling member, the shuttle-propelling member is caused to move away from the shuttle preferably at substantially the same velocity as the velocity of the shuttle. As described hereinbelow in connection with a specific embodiment of this invention, the shuttle-propelling member may be movable within a shuttle box, and, according to this invention, the shuttle upon being received by the shuttle box moves towards the shuttle-propelling member and comes into initial contact therewith when the shuttle-propelling member is moving in the same direction as the shuttle and at approximately the same velocity. Thereafter, the shuttle and shuttle-propelling member are smoothly but rapidly decelerated so that there is no sudden jar or shock when the shuttle is received by the shuttle box and is brought to rest by the shuttle-propelling member. Appropriate synchronizing or timing means

can be provided to accomplish this end, as will hereinafter be described.

In preferred practice of this invention, two shuttle-propelling members are provided on opposite sides of the loom for oscillation within oppositely-disposed shuttle boxes, the oscillatory movement of the shuttle-propelling members being synchronous but in opposite directions so that the shuttle-propelling members will first move towards each other and then move away from each other. When the shuttle-propelling members move toward each other, these members are first accelerated so as to propel the shuttle from one of the shuttle boxes toward the other. The shuttle-propelling members are decelerated while still moving in the shuttle-propelling direction, and come to rest and then have their motion reversed so as to move away from each other. In moving away from each other, the shuttle-propelling members are first accelerated, and the mechanism is synchronized so the shuttle will come in contact with the receiving member when the velocity of these members is approximately the same as the velocity of the shuttle. The shuttle and the shuttle-propelling members (including the shuttle-propelling member with which the shuttle has come in contact) thereafter are decelerated to rest position for the start of the shuttle-propelling stroke for the return flight of the shuttle. By way of more specific illustration, the cycle may be described as starting when the shuttle is in contact with the left-hand shuttle-propelling member, both of these members then being at rest in the extreme outward position of their strokes. The left-hand shuttle-propelling member is first rapidly accelerated toward the right, namely, inward toward the shed, pushing the shuttle ahead of it. When the shuttle and shuttle-propelling members attain maximum velocity, the crosshead is rapidly decelerated and the shuttle leaves it to fly through the shed. In the meanwhile, the opposite shuttle-propelling member has been undergoing the same motion, but oppositely directed, and the mechanism is synchronized so that these members attain substantially the same maximum velocity at substantially the same moment. While the shuttle is in flight from left to right, both members continue to be decelerated on their inward motion, come to rest, and are then rapidly accelerated outward away from the shed. Both members reach the maximum outward velocity which is substantially the same as the maximum inward velocity at a point in the travel which may be geometrically coincident with the point at which maximum inward velocity is developed. At substantially this point in the outward travel of the right-hand member, the shuttle which is traveling from left to right comes into contact with this member. At this moment, the velocity of the right-hand member is substantially the same as the velocity of the shuttle (disregarding the small loss of kinetic energy during flight). The velocity of the shuttle and the rate of movement of the shuttle-propelling members are synchronized so as to effect this predetermined timing. Since the shuttle and the right-hand member are moving in the same direction at substantially the same speed, there is virtually no impact shock. Thereafter, the right-hand member and the shuttle are decelerated and brought to rest in the extreme outward position. It is seen that, by this motion and timing of the shuttle-propelling members, the shuttle has been brought from the left shuttle box to the right shuttle box by rapid

but smooth acceleration up to the velocity of flight, then by free travel at this same velocity, and thereafter by rapid but smooth deceleration from substantially this velocity to zero velocity. By the same sequence of acceleration, free travel and deceleration, but in the opposite direction, the shuttle is brought from right to left, and this reciprocatory motion of the shuttle may be repeated so long as it is desired to continue operation. It is an advantage of the operations described for impelling and receiving the shuttle that no appreciable shocks resulting from sudden impacts occur. Moreover, the shuttle-propelling members are dynamically balanced so that there is very little vibration of the mechanism as a whole.

In the deceleration process described above, the decelerating force is smoothly applied to the shuttle by the crosshead or propelling member with which it is in contact. The reaction of this force on the mechanical train which operates the crosshead is such as to give back to the machine the kinetic energy of the shuttle, minus such losses as occur in ordinary machine friction. Thus, the kinetic energy is recovered with good efficiency instead of being lost entirely, as in conventional means, by impact and special friction to stop the shuttle. In the embodiment to be described, the shuttle-propelling members or crossheads have their motion imparted thereto by actuating means wherein resilient means contact both in supplying the energy for flight and in receiving energy during deceleration. But the mechanism as a whole does not function as a resilient mechanism because its motions are substantially rigidly determined as will be described. The absence of impact forces is important in any case, but is particularly advantageous in connection with loom shuttles comprising a gyro mechanism for eliminating or minimizing of impacts on the gyro bearings.

As is the case with any gyro mechanism, it is desirable that the bearing friction be kept small. When a gyro mechanism is embodied in a loom shuttle, it is desirable that the bearing friction be small not only to avoid substantial loss of energy of the gyro between actuating impulses, but also to minimize the tendency which arises from the bearing friction to cause the shuttle as a whole to rotate about the longitudinal axis of the gyro. Thus, when the rotational axis of the gyro is parallel to the longitudinal axis of the shuttle, bearing friction tends to rotate the unguided shuttle during its flight about its longitudinal axis. The actual amount of this rotation in any one traverse of the shuttle will be small because the bearing friction is small and because the duration of the flight of the shuttle is very short. However, such rotation is cumulative unless corrected. In any loom it is necessary that the angular position of the shuttle about its longitudinal axis be maintained substantially constant relative to the shuttle boxes for operation of the bobbin-changing mechanism and other devices. Moreover, when the shuttle comprises a gyro mechanism according to this invention, such definite orientation of the shuttle is desirable in order that power for actuating the gyro mechanism may be readily supplied by communication through and between the shuttle box and the casing member of the shuttle that is disposed about the gyro mechanism. According to this invention, means are provided for rotatably adjusting the disposition of the shuttle about its longitudinal axis so as to cause the shuttle to assume a predetermined angular position about

this axis and so that, in case the shuttle upon being received by the shuttle box has become displaced from the desired predetermined angular position, such displacement can be corrected. The means for correcting angular displacement of the shuttle about its longitudinal axis may take several forms. For example, the exterior of the shuttle may be provided with a portion having a non-circular cross-section which is adapted to register with a similar cross-section of the bore of the shuttle box so that the shuttle on entering the shuttle box will be brought to the predetermined desired angular position about its longitudinal axis relative to the shuttle box. Such means for correcting any angular displacement of the shuttle about its longitudinal axis involves impact of the shuttle with the shuttle box which receives the shuttle, and it is therefore preferable according to this invention to bring the shuttle to its position of rest within the shuttle box and to provide means whereby the shuttle when in a position of rest may be rotatably adjusted about its longitudinal axis in order to correct for any displacement from its desired angular position. One embodiment of such means is described in more detail hereinbelow.

In a preferred embodiment of this invention, the shuttle on completing its flight and making contact with the shuttle-propelling member or crosshead becomes latched thereto so as to prevent longitudinal relative motion between the shuttle and shuttle-propelling member until the latching means is released, which preferably occurs at the moment when the shuttle-propelling member reaches its maximum inward velocity or slightly before this moment. By providing such latch or securing means, the important advantage is gained of readily preventing release of the shuttle when for any reason such prevention is desired, for example, when the loom is being started and has not yet reached operating speed or when any of the several safeguards on the loom signals the mechanism to stop picking. It is preferable that the securing or latching means be adapted to co-act with an engageable member presented by the shuttle so that the shuttle may be adjusted rotatably about its longitudinal axis relative to the shuttle-propelling member while the securing means is engaged with the engageable member presented by the shuttle.

In order to attain the advantages of this invention to maximum degree, the features of this invention which have been described hereinabove are preferably employed in combination, although it is apparent that it is not necessary that all of the features of this invention be employed simultaneously and that the advantages of this invention may be attained at least to some degree when the individual features of this invention are employed separately so as to obtain the benefits resulting from the employment of any such feature of my invention. Further purposes, features and advantages of this invention will be apparent by reference to the following description of certain specific embodiments of this invention which, in order to afford a clearer understanding of this invention, are shown diagrammatically and by way of illustration in the accompanying drawings, wherein

Fig. 15 is a sectional view of the shuttle box shown in Fig. 14 taken on the line 15-15 of Fig. 14;

Fig. 16 is a sectional elevation of the outwardly-flared shuttle-receiving end of the shuttle box shown in Fig. 14 and shows the shuttle entering the shuttle box with its disposition about its longitudinal axis displaced substantially from that required for registry of the peripheral contours of the end of the shuttle with the internal contours of the shuttle box; and

Fig. 17 is a sectional view of the shuttle box and shuttle shown in Fig. 16 taken on the line 17-17 of Fig. 16.

Referring to the embodiment of this invention as shown in Figs. 1 to 11, oppositely-disposed shuttle boxes 20 and 20a, together with the shuttle-propelling mechanisms associated therewith, are mounted on the frame 21 of the loom.

Since the shuttle boxes and the shuttle-propelling

mechanisms at the opposite sides of the shed of the loom are complementary, that is, have right-and-left symmetry, the description of this invention which follows is directed specifically, as far as detail of structure is concerned, mainly to the shuttle box and associated mechanisms shown at the lefthand side of Fig. 1.

For supporting the shuttle box 20, a bracket 22 is rigidly secured to a member of the loom frame 21. Upstanding adjacent the ends of the bracket 22 are the bearing members 23 (see Figs. 2 and 3) through which passes the rod 24. A U-shaped frame member 25 is carried by the rod 24 and includes the collar members 26 which surround and support the shuttle box 20 from the ends of the arms of the frame member 25. Since the frame member 25 is carried by the rod 24 which is rotatable within the bearing members 23, it is apparent that the vertical position of the shuttle box 20 can be elevated and lowered by effecting a rocking motion of the frame member 25 about the axis of the rod 24. This rocking motion can be effected and controlled as desired in synchronism with the rotation of the power shaft 27. Power for rotating the power shaft 27 can be supplied by any suitable means such as a motor (not shown). Any suitable means for rocking the frame member 25 to raise and lower the shuttle box 20 in proper timing with the rotation of the power shaft 27 may be utilized. For purposes of illustration, such means is shown as consisting of the cam 28 which rotates with the power shaft 27 and which co-acts with the cam roller 29 that is carried by the cam rod 30. At the upper end of the cam rod 30 is a bearing member 31 for the bearing pin 32 which is carried by the members 33 that are rigidly secured to the frame member 25. In order that the cam roller 29 may be maintained in proper position relative to the cam 28, a yoke member 34 (Fig. 2) is provided which is rigidly secured to the rod 30 and which fits about the power shaft 27 so as to prevent lateral movements thereof normal to the power shaft while at the same time permitting elevation and lowering of the cam roller to effect the desired vertical movement of the rod 30. The cam roller 29 effects positive upward movement of the rod 30. The downward movement of the rod 30 for maintaining the cam roller 29 in contact with the cam 28 is effected by the compression spring 35 which is disposed between a member 36 which is rigid with the bracket 22 and which is apertured for free passage of the rod 30 therethrough and the collar 37 which is fixed to the rod 30 by any suitable means such as a set screw, pin or the like. The cam track provided by cam 28 for controlling the vertical movement of the cam roller 29 is arranged with respect to the power shaft 27 for imparting a slight rocking motion to the frame 25 so that the shuttle box 20 will be reciprocated vertically through a small distance. As will be described more in detail hereinbelow, the vertical movement of the shuttle box under the influence of the actuating means above described is timed so as to compensate for the fall of the shuttle under gravity during free flight. The timing of these movements of the shuttle box in synchronism with the other mechanisms will be described more in detail hereinafter.

Mounted for longitudinal reciprocation within the shuttle box 20 is the shuttle-propelling member which is indicated generally by the reference character 38 (see, for example, Fig. 4). For brevity, the shuttle-propelling member will also be referred to hereinafter as the crosshead.

This crosshead has an opening 39 (see Fig. 5) extending therethrough and carries the bearing pin 40 which extends across the opening 39 and about which is rotatably disposed the bearing member 41 that is integral with the upper end member 42 of the actuating arm 43 or "picker stick." The upper end member 42 of this arm is telescopically slidable within the actuating arm 43 so as to permit the required change in over-all length of the combination 42-43 during the horizontal reciprocation of the crosshead 38 within the shuttle box. The shuttle box has an elongated aperture 44 along the bottom thereof to permit reciprocation of the crosshead together with its actuating arm relatively to the shuttle box.

The actuating arm 43 is pivotally mounted for permitting reciprocatory motion of the upper end thereof on the bearing pin 45 (see Fig. 1) which is carried by the bracket 46 that is secured to the loom frame 21. The loom frame at or near the point where the bracket 46 is attached thereto may be reinforced by one or more tie rods 47. Carried by the actuating arm 43, is the cam roller 48 which is disposed for contact with the cam track 49 presented by the large bell-shaped cam member 50 that is secured to and rotates with the power shaft 27. In order to maintain the cam roller 48 in contact with the cam track 49 and to provide power for moving the crosshead on its shuttle-propelling stroke, any suitable means may be used, although it is preferable according to this invention to provide resilient means in the form of gaseous fluid under compression. For this purpose, a piston and cylinder may be used as shown in greater detail in Fig. 7. The cylinder 51 may be supplied with compressed air, for example, from any suitable source by a flexible air line 52 (see Fig. 1). For example, a reservoir (not shown) containing air under high pressure may at all times be connected with the interior of the cylinder 51 by the line 52. The cylinder 51 is open to the atmosphere at the inner end and the piston 53 is slidable therein, the piston 53 being connected to the piston rod 54 that passes through the packing 55 and that is connected to the actuating arm 43 by the bearing member 56. The action of the compressed air in cylinder 51 against the piston 53 urges the cam roller 48 against the cam track 49 with a force that depends upon the superatmospheric pressure within the cylinder 51. It is apparent that resilient means other than that afforded by compressed gaseous fluid may be utilized, for example, a spring which is disposed so as to at all times urge the cam roller 48 against the cam track 49 of the cam member 50 and which is adapted to provide sufficient force for propelling the crosshead to impart desired shuttle velocity. The cylinder 51 is carried by the loom frame 21 and is mounted for rocking movement by the bearing brackets 57 which are secured to the loom frame and which include the bearings 58 for the pin 59 that passes through the ears 152 (Fig. 2) protruding from the open end of the cylinder 51. The brackets 57 on opposite sides of the loom may be tied together for structural reinforcement.

It is apparent from the foregoing description of the actuating arm 43 and the cam mechanisms associated therewith that the upper end of the actuating arm 43 can be reciprocated so as to reciprocate the crosshead 38 within the shuttle box 20 so as to propel the shuttle from

the shuttle box and return the crosshead to its extreme outer position. In Fig. 1 and Fig. 4, the crosshead 38 and actuating arm 43 are shown in the extreme outer position. Upon operating the mechanism so as to rotate the cam member 50 in a clockwise direction viewed from the right, the action of the air within the cylinder 51 causes the actuating arm 43 and crosshead to move inwardly for propelling the shuttle from the shuttle box, this motion being controlled by the slope of the cam track 49. This motion as controlled by the cam track is one of rapid but smooth acceleration until maximum velocity is reached at approximately the mid-point of the travel of the crosshead and then deceleration which is concluded rapidly and smoothly until the point of extreme inward travel of the actuating arm 43 is reached. The extreme inward position of the actuating arm 43 is shown in Fig. 7. Upon further rotary movement of the cam member 50, the actuating arm 43 is returned to its original outward position, this movement being impelled and controlled by the cam track 49 so as to effect rapid and smooth acceleration until maximum velocity is reached approximately at the mid-point of the travel of the crosshead, the motion thereafter being decelerated so as to conclude rapidly and smoothly. The cam track is so designed that there will be a period of dwell at each extreme position of the actuating arm 43 and crosshead 38. The timing of the motion of the actuating arm will be illustrated and described more fully hereinbelow in connection with Fig. 12.

In apparatus embodying this invention, it is preferable, as stated hereinabove, that the actuating arm 43 be moved in the shuttle-propelling direction by resilient means which co-acts with the shuttle-propelling mechanism as a whole so as to supply the power for propelling the shuttle. By thus using resilient means to propel the shuttle, an easily operated safety feature is provided in that if for any reason it is necessary to stop the picking motion, the movement of the actuating arm 43 can be readily stopped without elaborate mechanism such as would be required if the actuating arm were to be propelled in both directions by positively acting mechanical means such as a groove cam.

It has been mentioned hereinabove that it is preferable to provide securing means whereby the shuttle may be secured to the shuttle-propelling member or crosshead so as to prevent relative longitudinal movement between the shuttle and the crosshead after contact between these members has been established. One form of securing means is illustrated and is described below, particularly in connection with Figs. 4, 5 and 6. The securing means that is shown comprises a split tube 60 which provides a plurality of spring fingers 61 extending towards the shuttle. Each of these spring fingers has an inwardly extending portion 62 and the latch part 63. The end of the shuttle is provided with a groove 64 that affords an engageable member adapted to be engaged by the latch parts 63 of the securing means. The split tube 60 is secured to the crosshead by any suitable means such as the threading 65. Inside the split tube 60 rides the expander 66 to which is attached the rod 67 having an enlarged end 68. The spring 69 holds the expander 66 away from the inwardly extending portions 62 of the spring fingers 61. A lever 70 is mounted within the opening 39 in the crosshead for pivotal movement about the pin 71 which is

carried by the crosshead 38 across the opening 39. A pin 72 projects from the lower end of the lever 70, and at the upper end of the lever 70 is the head 73 which is adapted to abut against the member 68 so that, upon rotating the lever 70 about the pin 71 from the position shown in solid lines to the position shown in dotted lines in Fig. 4, the expander becomes pushed against the inwardly extending portions 62 of the spring fingers 61 so as to free the latch parts 63 from the groove 64 in the shuttle thereby releasing the shuttle from the crosshead at the desired time. In order to effect this movement of the lever 70 so as to release the shuttle at the proper time, a bar 74 (Figs. 2, 4 and 5) is provided which is carried by the collars 75 which surround the shuttle box 20 so that these collars may be rotated, together with the bar 74, about the longitudinal axis of the shuttle box. The position of the bar 74 is controlled, for example, by the movable rod 76 which is pivoted to the ear 77 (Fig. 5) that depends from the bar 74. When the bar 74 is in its normal position as shown in Figs. 4 and 5, the pin 72 carried by the lever 70 will come into contact with the end 78 of the bar 74 during the shuttle-propelling motion of the crosshead, and when this occurs the pin 72 is caused to ride onto the bar 74, thereby bringing the lever 70 to the position shown in dotted lines in Fig. 4 so as to force the expander inward and thus to release the shuttle from the securing means. The timing of the release of the shuttle is determined by the location of the end 78 of the bar 74. Ordinarily, the securing means is released at or shortly prior to the time when the crosshead and shuttle attain maximum velocity during the shuttle-propelling stroke of the crosshead. It is apparent that upon the return stroke the expander 66 becomes retracted as soon as the pin 72 reaches the end 78 of the bar 74 so that the latch parts 63 will engage the groove 64 in the shuttle on the return flight of the shuttle. A stop 132 (Figs. 4 and 6) prevents or limits motion of the part 73 away from part 68.

It is an advantage of the device shown that the securing means for securing the shuttle to the crosshead can be prevented from releasing the shuttle under certain conditions. As above stated, the bar 74 is carried by the collars 75 which are rotatable about the shuttle box. By pulling the rod 76, the bar 74 can readily be moved out of the path of the pin 72 so that release of the shuttle from the crosshead can be prevented. The rod 76 may be associated with any stop mechanism or group of stop mechanisms associated with the loom so that release of the shuttle from the crosshead may be prevented whenever this may be desired. Thus, two independent means are provided for stopping the flight of the shuttle, one being the means of holding back the picker stick conventionally employed; the other the means just described.

Referring to Figs. 8 to 11, an example of a loom shuttle provided with a gyro mechanism according to this invention is shown. The loom shuttle comprises the tubular body 79 which is secured to the annular member 80. Also secured to the annular member 80 is the casing member or shuttle cap 81. The shuttle cap 81 encloses a gyro 82 which is the rotor or rotatable inertia member of the gyro mechanism for stabilizing the shuttle in its flight. The gyro 82 rotates on the bearings 152 about the shaft 83 and is held endwise thereon by the nuts 84. The rotor shaft 83 is carried by the member 85 which is secured to or formed integral with the annular member 80. The bob-

bin clip 86 may be of any conventional design and may be carried by the annular member 80. The bobbin 87 is shown in position. The top and bottom of the tubular shuttle body 79 are provided with openings 88 (Fig. 10) which provide entry and exit openings for the bobbin so that the bobbin can be changed by known bobbin-changing mechanisms. Slots 89 and 90 are provided in the tubular shuttle body 79 as is conventional for entry of the bobbin feeler and for entry of the cutter.

The periphery of the rotor or gyro of the gyro mechanism is provided with a plurality of buckets or vanes 91 which constitutes deflectors for a jet of air which is impinged thereon to cause the rotor or gyro to rotate at high speed. Openings 92 (Fig. 9) in the shuttle cap 81 are provided for admitting and exhausting compressed air and they are positioned with reference to the deflectors 91 so that a jet of air passing therethrough causes rapid rotation of the gyro 82. The compressed air is used to impel the gyro 82 when the shuttle is at its extreme outward position within the shuttle box. In order that this may be accomplished, the shuttle box is provided with aperture means 93 and 93a (see Figs. 3 and 9) which register with the openings 92 in the shuttle cap when the shuttle comes to rest in its extreme outward position in the shuttle box. The aperture means 93 has associated therewith an air line 94 which is connected to a source (not shown) of compressed air so that the air under compression may be discharged as a jet through the aperture means 93 in the shuttle box and through the openings 92 in the shuttle cap for impelling the gyro of the gyro mechanism.

It is preferable to cut off the jet of compressed air when the shuttle is not in its position of rest in its extreme outward position within the shuttle box. This may be accomplished by the valve 95 in the air line 94 which can be actuated from the power shaft 27 by appropriate timing mechanism. In the particular device shown, the power shaft 27 is provided with the cam 96 (Fig. 1) on which rides the cam roller 97 that is carried by the cam rod 98 similarly to the cam roller 29 which is carried by the cam rod 30. A yoke 149 secured to the cam rod 98 straddles the power shaft to maintain the position of the cam roller 97. The upper end of the cam rod 98 is pivotally connected to the arm 99 (Figs. 1 and 3) which is attached to a rock-shaft 100 that is rotatably mounted within the hollow casting member 101 secured to the bracket 22. Secured to the opposite end of the shaft 100 is the arm 102, the upper end of which abuts against the valve 95. The compression spring 103 between the fixed stop 104 and the collar 105 fastened to the rod 98 causes the cam roller 97 to follow the cam 96 and urges the arm 102 against the valve 95 so as to permit flow of air through the line 94. The cam 96 is of a shape appropriate for permitting the spring 103 to open the valve 95 when the shuttle first reaches its position of rest in the shuttle box, or just prior thereto, and for retracting the arm 102 from the valve 95 when the shuttle starts its motion for discharge from the shuttle box. The valve 95 may be of any suitable type such that, when pressure is brought thereagainst by the arm 102, the valve is opened and such that it will automatically close as soon as the arm 102 is moved away therefrom.

It is apparent that the angular position of

the shuttle about its longitudinal axis relative to the shuttle box should be controlled so that the openings 92 in the shuttle casing may come into registration with the aperture means 93 in the shuttle box for the purpose of directing the compressed air as a jet against the deflectors 91 on the gyro. Accurate registration is not essential here, because the openings 92 may be extended circumferentially to avoid the necessity of their accurate registration with the jet 93, but it is necessary to control the angular position of the shuttle so as to permit operation of the bobbin-changing mechanism and operation of the feeler and cutter mechanisms. In order that this angular orientation of the shuttle may be controlled and in order to adjust such orientation of the shuttle in the event of its departure from its desired angular position, means is provided for making such adjustment automatically. Referring particularly to the means for making such adjustment which is shown in Figs. 1, 2, 3, 8 and 11, the body portion 79 of the shuttle has a tapered slot 106 therein. For co-action with the slot 106, the pin 107 (Fig. 11) is provided which is fixed to the shaft 108 that is rotatably carried by bearing members 109 secured to the top of the shuttle box 20. The pin 107 is normally maintained in the position shown in Fig. 1 and in solid lines in Fig. 11 by torsion spring 110 (Fig. 3). However, by rotating the shaft 108 to bring the pin 107 to the position shown in dotted lines in Fig. 11, the pin 107 is made to enter the tapered slot 106. When this occurs, it is apparent that if the shuttle is not in its proper angular position the shuttle will be rotated so that this angular position will become adjusted to the position desired. This is caused to occur after the shuttle has been brought to rest in its extreme outer position. The adjustment is thus made without the occurrence of appreciable impact such as may occur in the modification shown in Figs. 16 and 17, for example. At the time this adjustment is made, utilizing the embodiment of this invention which is shown, the securing means for securing the shuttle to the crosshead is in engagement. It is apparent, however, that the design of the securing means is such as to permit of this adjustment.

The pin 107 may be caused to move to the position shown in dotted lines in Fig. 11 by any suitable means. The means which is shown by way of illustration consists in a cam 111 (Fig. 1) against which the cam roller 112 rides. The cam roller 112 is carried by the lower end of the slotted guide member 110 which is secured to the bottom of the cam rod 113. The cam rod 113 is urged upwardly by the compression spring 114 which is disposed between the bracket 115 fixed to the loom frame and the collar 116 fixed to the cam rod 113. The upper end of the cam rod 113 is pivotally secured to one end of the lever arm 117, the other end of the arm 117 being secured to the rock-shaft 118 which passes through the bearing casting 119 (Fig. 3). Affixed to the other end of the shaft 118 is the arm 120, the upper end of which carries a head 121 for abutting against the end of the arm 122 which is rigid with the small shaft 108 that carries the pin 107. Whenever the cam rod 113 is permitted to move upwardly as controlled by the cam 111, the arm 120 is rocked so as to rotate the small shaft 108 and move the pin 107 to the position shown in dotted lines in Fig. 11. When the cam 111 moves the cam rod 113 downwardly, the arm

120 is rocked in the opposite direction and the spring 110 moves the pin 107 to the position shown in solid lines in Fig. 11. The cam 111 is so designed that these movements will take place during the period when the shuttle is at rest in its extreme outward position of travel within the shuttle box. With the arrangement shown, if the position of the shuttle in the shuttle box should become displaced to such an abnormal extent that the pin 107 cannot enter the tapered slot 106, it is apparent that no damage or breakage of the mechanism will occur, for the force for moving the pin 107 to the position shown in dotted lines in Fig. 11 is supplied solely by the resilient spring 114 rather than by a non-resilient mechanical action. In the event of any such emergency whereby the pin 107 may be prevented from normal entry into the tapered slot 106, a suitable stop mechanism can be provided that is adapted to cause cessation of picking.

In Fig. 8, the detail of the gyro mechanism at one end only of the shuttle is shown. For stabilizing the shuttle in its flight, the gyro mechanism may be located at one end only of the shuttle. However, it is preferable that the gyro mechanism shown at the lefthand end of the shuttle be duplicated within the shuttle cap 81a at the righthand end of the shuttle which is shown in Fig. 8. The tapered slot 106 may be included in like but complementary position in the portion of the shuttle body 79 which is cut away in Fig. 8 in order to show the mounting for the gyro mechanism and bobbin clip within the shuttle, but such duplication of slot 106 would require lengthening the shuttle body to avoid interference between pin 107 and the bobbin-changing mechanism. It is preferable to use only one slot 103 and to place the shuttle orienting parts 107, 108, 109, etc., on the righthand side in such position as to operate in this one slot rather than to use the right-and-left symmetry shown. It is to be understood that the shuttle as a whole is made as light and as small as is practicable and that the gyros are driven at very high speed, which may be of the order of 30,000 to 40,000 revolutions per minute or even more. The compressed air impelling means, as shown, indicates that the left gyro receives its impulses only when in the lefthand shuttle box, and the right gyro when in the righthand shuttle box, i. e., each gyro receives one impulse in two picks. However, the aperture means in each shuttle box may be duplicated so that each gyro will receive an impulse for each pick.

In connection with the construction of the shuttle, it is to be noted that the shuttle caps 81 and 81a include an enlarged portion 123 in cap 81 and 123a in cap 81a. In other words, the shuttle is provided with a tubular portion which constitutes the body of the shuttle, and at each end of the body of the shuttle there is provided an end portion which has a greater cross-sectional dimension than the tubular body portion of the shuttle. It is these enlarged end portions of the shuttle that make contact with the shuttle box. This construction is desirable in order to avoid contact between the shuttle box and the middle portion of the shuttle during entry of the shuttle into the shuttle box.

The shuttle box 20 is provided with an opening 124 (see Figs. 3 and 10) in the upper portion thereof which comes into registration with the openings 89 in the shuttle when the shuttle is in rest position within the shuttle box so that the bobbin-changing mechanism may operate there-

through. The side of the shuttle box may be provided with a longitudinally-extending opening 125 (see Figs. 1 and 10) adapted to register with the openings 89 and 90 in the shuttle for access of conventional feeler and cutter mechanisms (not shown). The end of the shuttle box is provided with a flared portion 126 so as to facilitate and guide the entry of the shuttle into the shuttle box in case of minor misalignment between the shuttle and the shuttle box when the shuttle enters the shuttle box on approaching the end of its flight.

As mentioned above, the foregoing description has referred primarily to the lefthand shuttle mechanism shown in Fig. 1. It is to be understood that the righthand shuttle mechanism is symmetrical with the lefthand shuttle mechanism except for certain details like the bobbin-changing mechanism, possibly the shuttle-orienting mechanism, etc. Thus, the shuttle boxes 20 and 20a are oppositely disposed for effecting reciprocatory flight of the shuttle therebetween through the shed of the loom. Accordingly, the parts shown in the righthand shuttle mechanism of Fig. 1 are in the main the same as in the lefthand shuttle mechanism and some of these parts have been indicated by the same characters used for identifying the parts in the left hand shuttle mechanism where this has been deemed desirable for the purpose of clarity in the showing.

With regard to the operation of the apparatus shown in Figs. 1 to 11, the timing and synchronization of the operations may be described starting with the position of the parts as shown in Fig. 1. It may be assumed that the apparatus has been brought up to operating speed and that the shuttle is momentarily in its position of rest at the extreme outer end of the lefthand shuttle box. By the action of the compressed air jet, the gyro of the gyro mechanism in the shuttle has been brought up to its desired high speed of rotation. Upon rotation of the power shaft 27 in a clockwise direction (viewed from right), the actuating arms 43 become accelerated inwardly and reach maximum velocity at about the midpoint of their inward strokes. At this point, the securing means for securing the shuttle to the lefthand shuttle-propelling member or cross-head is released. Moreover, during this motion of the crosshead in the shuttle box, the shuttle box as a whole is moved upwardly through a slight distance, its upward motion being accelerated synchronously with the accelerated motion of the shuttle. When the shuttle is released from the crosshead, the lefthand shuttle box continues to rise and at the same time the crosshead is decelerated until it reaches its extreme inward position. When this occurs, the upward movement of the shuttle box is decelerated, but prior to this time the shuttle has been ejected from the shuttle box so that there is coupled with the horizontal velocity of the shuttle a small upward velocity component as it leaves the shuttle box. This upward component compensates for the action of gravitation on the shuttle during its period of free flight. While the lefthand mechanisms have been undergoing the movements above described, the righthand mechanisms have been undergoing the same movements in exact synchronization with the movements of the lefthand mechanisms but with the lateral movements in the opposite direction.

While the shuttle is in its flight from the lefthand to the righthand of the shuttle box, the

actuating arms 43 reach their extreme inward position and the shuttle boxes reach their maximum elevation. Thereafter, the actuating arms 43 begin their outward movements which are accelerated so as to reach maximum velocity at about the mid-point of the stroke of the arms 43. At the same time, the shuttle boxes are moved downwardly. The timing of the mechanisms by virtue of the operation of the power shaft 27 and the cam mechanisms associated therewith in relation to the spacing of the shuttle boxes and the velocity of the shuttle is such that the shuttle reaches the end of its flight, namely, the moment when the shuttle comes into contact with the crosshead in the righthand shuttle box, when this crosshead is moving in the direction of the shuttle at substantially the same velocity as the velocity of the shuttle away from the shed. Moreover, as the shuttle enters the righthand shuttle box, the righthand shuttle box is caused to be moved downwardly at substantially the same rate as the rate of gravitational fall of the shuttle at the end of its flight. The shuttle therefore enters the shuttle box without any jarring impact either due to becoming aligned with the shuttle box or due to a sudden stopping of the horizontal or vertical momentum of the shuttle. When the shuttle comes into contact with the crosshead in the righthand shuttle box, the securing means becomes engaged with the shuttle and the shuttle and the righthand crosshead are decelerated until these parts come to rest position at their extreme outer position of travel.

It is to be noted that the kinetic energy of the shuttle is not dissipated in the form of friction and impact in being brought to rest in the shuttle boxes, but is received by the resilient means which propels the arm 43 on its shuttle-propelling stroke and which urges the cam roller 48 carried by the arm 43 against the cam track 49 so that the position and movement of the arm 43 are at all times controlled. Normally, the motor which supplies power for rotating the power shaft 27 acts against this resilient means in moving the actuating arms 43 outwardly as a result of rotation of the cam member 50. However, to the extent that the kinetic energy of the shuttle in being decelerated urges the actuating arm 43 toward its extreme outward position, to substantially the same extent the power required for rotating the shaft 27 to effect this movement is diminished and the kinetic energy of the shuttle is recovered instead of being dissipated and lost. The energy thus received and recovered is then released in propelling the shuttle from the shuttle box, and improved operating efficiency is obtained.

When the shuttle reaches its extreme outward position in the righthand shuttle box, the valve 95 in the air line is opened so as to direct a jet of air against the deflectors on the periphery of the gyro of the gyro mechanism within the shuttle. At the same time (or earlier), the pin 107 is moved so as to correct any displacement (within limits) of the angular position of the shuttle about its longitudinal axis which might have occurred. At the end of the period of rest of the shuttle (or earlier), the pin 107 is moved out of the way and the jet of air is cut off, whereupon the righthand actuating arm 43 starts its inward shuttle-propelling stroke for flight of the shuttle from the righthand shuttle box to the lefthand shuttle box, the operations being the same as above described except that the shuttle now moves from right to left. In loom operation, this rapid re-

ciprocatory travel of the shuttle is continued until such time as it is desired to stop picking for any reason. At such time the part 76 can be pulled to move the bar 74 so that the pin 72 will not come in contact therewith thereby preventing release of the shuttle from the crosshead with which it may be in contact. Alternatively, the picker motion can be stopped as in conventional looms without stopping the power shaft, by blocking the arm 43 in extreme outward position by the stop 151 which is normally out of the path of the arm 43 as shown in solid lines in Fig. 2 but which can be moved to the position shown in dotted lines in Fig. 2 so as to prevent inward movement of the arm 43. This is permitted since the force for propelling the arm 43 inwardly is afforded by the compressed air in cylinder 51 or other resilient means.

The timing and synchronization of the crossheads, the shuttle boxes and the shuttle in connection with a specific application of the principles and sequences of operations hereinabove generally described are indicated for purposes of exemplification by the graphic representation shown in Fig. 12. In this graphic representation the position of the crossheads, shuttle boxes, and shuttle are plotted against time and also against the angular degree of rotation of the cam shaft.

The operation is shown as starting with the shuttle in the lefthand shuttle box when the crossheads are in the extreme outer position indicated at A and A' respectively, the solid lines representing the positions of the crossheads. At this starting point the crossheads are spaced furthest apart from each other and are at rest. Zero seconds and zero degrees of rotation of the cam shaft have been selected as the starting point which occurs at the mid-point of the period of dwell in this position of rest. At the end of the period of rest both crossheads are moved inwardly with rapid but smooth acceleration as indicated by the curves until maximum velocity is reached at the points P and P' simultaneously. At this moment the shuttle leaves the lefthand crosshead at maximum horizontal velocity (in this instance, say, 37 meters per second). The crossheads thereafter are smoothly decelerated at the rate indicated by the curves and come to rest at their extreme inward positions where they remain stationary as indicated at B and B'. The crossheads are then accelerated outwardly and attain maximum velocity at the points Q and Q', the points Q and Q' being substantially coincident with P and P', and the velocity of the crossheads at Q and Q' being the same as the velocity at the points P and P' but in the opposite direction. During the period within which the crossheads have been moving from the points P, P' to the points Q, Q', the shuttle has been in free flight. The timing and synchronization of the device are such that the shuttle will arrive at Q' at the instant that the crosshead arrives at Q', and when at this point the shuttle and crosshead are moving in the same direction at the same velocity, except for any slight deceleration of the shuttle in its flight due to aerodynamic forces, drag of the weft yarn, etc. The crossheads and the shuttle, the shuttle being now in contact with the righthand crosshead, are then decelerated smoothly at the rate indicated by the curves, the crosshead coming to rest again in extreme outer position at C and C'. During the period of rest the gyro of the gyro mechanism within the shuttle is impelled, as by the jet of compressed air 75 in the manner above described, and at the same

time the angular position of the shuttle about its longitudinal axis relative to the shuttle box is adjusted by action of the pin 107, if any such adjustment is necessary. The crossheads are then moved inwardly, the shuttle now being propelled from right to left at the same velocity that it was propelled from left to right, the crossheads coming to rest at their innermost positions at D and D'. Upon the next movement outward of the crossheads, the shuttle is received by the lefthand crosshead at Q when the shuttle and crosshead are moving at approximately the same velocity and the crossheads come to rest again at E and E' so as to complete the cycle of operations. When the shuttle is in its position of rest in the lefthand shuttle box, the gyro mechanism in the shuttle is again impelled and the angular position of the shuttle about its longitudinal axis is again adjusted.

With regard to the vertical motion of the shuttle boxes in the embodiment shown, the shuttle boxes are in their lowermost position at A and A' at the start of the cycle of operations. The dotted lines X and X' indicate the rise and fall of the shuttle box as controlled by the actuating and synchronizing mechanisms. The shuttle boxes at all times are axially parallel and axially in line in this embodiment. It is to be noted that when the crossheads are moved inwardly, the shuttle boxes at the same time are first accelerated in their upward movement and then decelerated, the maximum upward velocity of the shuttle boxes being at M and M', this point being reached at the instant the crossheads are at points P and P' respectively when the shuttle is released from the crossheads for flight through the shed. Thus, an upward velocity is imparted to the shuttle as it leaves the lefthand shuttle box. The shuttle boxes attain maximum rise when the crossheads are in their extreme inner position and descend during the outward stroke of the crossheads, the downward velocity of the shuttle boxes reaching its maximum at the points N and N' which is at the same instant that the crossheads reach points Q and Q', and this downwardly velocity being the same as the upward velocity of the shuttle boxes at points M and M'. In traveling from left to right, the upward component of the velocity of the shuttle after it leaves the lefthand shuttle box is first reduced to zero when the shuttle reaches the highest point of its parabolic trajectory, and the motion of the shuttle thereafter acquires a downward component and the timing is synchronized so that the vertical position of the shuttle is the same at the end as at the start of its flight and so that the downward velocity of the shuttle boxes at N and N' is the same as the downward velocity of the shuttle when it reaches the point Q' in being received by the righthand shuttle box at the end of its flight. In other words, when the shuttle reaches the end of its flight and is being received by the righthand shuttle box, the rate of fall of the shuttle is substantially the same as the downward velocity of the shuttle boxes. In the example shown in Fig. 12, the final downward velocity is the same as the initial upward velocity, and the highest point of the shuttle trajectory is in the center of said trajectory. The shuttle boxes are brought to rest in their lowermost position at C and C' and the same movements are repeated in causing the shuttle to pass from the extreme right to the extreme left position.

The diagram in Fig. 12 has been made for 0.1 second total time of cycle for one pick with 1½

meters of free flight; the horizontal scale for horizontal shuttle movement is about 1:10, and for vertical movement of shuttle box about 2:1. The maximum horizontal velocity is about 37½ meters per second; maximum vertical velocity about 19 centimeters per second. But it is to be understood that the operations indicated graphically in Fig. 12 are merely illustrative and that the timing may be changed depending upon the desired velocity of the shuttle in its flight and upon the length of flight of the shuttle. However, as shown by Fig. 12, the maximum velocity of the shuttle propelling members, which as aforesaid is substantially the same for each member and in each direction of travel, is attained at points in the strokes of the shuttle propelling members that are spaced apart by a distance substantially equal to the product of said maximum velocity of one of the shuttle propelling members in its shuttle impelling stroke and a succeeding moment of maximum velocity of the other of the shuttle propelling member in its shuttle receiving stroke. Thus, according to the specific example illustrated in connection with Figure 12, the aforesaid maximum velocity of 37.5 meters per second is attained when the left hand shuttle propelling member is at the point P and the shuttle concludes its free flight through the aforesaid 1.5 meter distance of free flight from the point P to the point Q¹, at which the other shuttle propelling member attains the same aforesaid maximum velocity on its shuttle receiving stroke, after the elapsed period shown in Fig. 12 of .04 second. Since said maximum velocity of 37.5 meters per second multiplied by the free flight time interval of .04 second is 1.5 meters, it is apparent that the distance between the points P and Q¹ is the product of the maximum velocity attained by the shuttle propelling members at the points P and Q¹ and the time interval between the moment when the left hand shuttle propelling member is at the point P in its shuttle propelling stroke and the succeeding moment when the right hand shuttle propelling member is at the point Q¹ in its shuttle receiving stroke. The same relationship also applies on the return flight of the shuttle from P¹ to Q. Moreover, when the mechanism is designed for movements of the parts as indicated in Fig. 12, it is apparent that each of the crossheads alternately travels inwardly and then outwardly again when the shuttle is not in contact therewith. This is preferable because the mechanism thereby is maintained in dynamic balance and vibration is minimized. However, it is not necessary that the mechanism be so designed. Thus, when the lefthand crosshead reaches its innermost position at B, it may remain in this position until this crosshead is moved outwardly between D and E without being returned to the C position during this interval. The righthand crosshead may be actuated similarly but alternately with respect to the left hand crosshead. Similar remarks apply to the vertical movements.

As previously mentioned, the method for compensating for vertical travel of the shuttle due to the action of gravity during free flight is capable of being varied widely. For instance, instead of having the high point of the trajectory come in the middle of its flight, the high point may come, as an illustration, at the end of its flight. This can be achieved by modifying the vertical-displacement time curve so that its slope at M and M' is twice that shown in Fig. 12, so as to impart twice as much vertical velocity to the shuttle

boxes, during propulsion, and by further modifying said curve as shown at Z and Z' of Fig. 12 so that the shuttle boxes are in their highest positions during reception of the shuttle. In this modified case, as in the previous one, shuttle box and shuttle have equal vertical velocities when the box receives the shuttle, but, as indicated, in this modified case the said vertical velocity is zero.

In Fig. 13, alternative means is shown for actuating a gyro mechanism contained in the shuttle box, such means in this case being electrical. The shuttle may be of the general construction above described including the body portion 19 and the annular member 80. The gyro mechanism in this case, however, is in the form of an electrical motor which conveniently may be designed for operation from a source of three phase alternating current of suitable frequency for the high speed required. In the form shown, the stator 128 is carried by the rod 129 which is coaxial with the longitudinal axis of the shuttle and which is rigidly carried by the member 130 that is secured to the member 80. The rotor 131, which is the armature of the motor and may, for example, be of conventional squirrel cage design, rotates about the rod 129. The field of the stator is connected to the conductor rings 134 on the shuttle cap 133. These rings are insulated from each other by the insulating material 135 and are electrically connected to the stator 128 by the connections 136. The shuttle box 137 may be the same as the shuttle box 20 except that there is secured thereto a brush holder 138 from which the brushes 139 extend for establishing electrical contact respectively with the rings 134 when the shuttle is in its normal rest position within the shuttle box. The brushes are connected to lines 140 which in turn are connected to any suitable source of electric current. It is apparent that when the shuttle comes to its rest position within the shuttle box 137, the electrically operated gyro mechanism within the shuttle is connected to the source of electric power which is effective to impel the rotor of the gyro mechanism for causing rapid rotation thereof. In the device shown, both the interior of the shuttle box and the periphery of the shuttle are of circular cross section, and by providing the rings 134 extending about the periphery of the shuttle cap 133, electrical connection can be established for operating the electrically operated gyro mechanism regardless of the angular position of the shuttle about its longitudinal axis relative to the shuttle box. However, since such angular position of the shuttle is normally maintained nearly constant, it is not necessary that the rings 134 extend completely around the periphery of the shuttle cap, for these rings may, if desired, extend only partly around the periphery of the shuttle cap or may be of virtually the same extent as the ends of the brushes 139. While for convenience these brushes are shown in one plane, they are preferably placed in different planes to facilitate prevention of short-circuiting during shuttle movements.

In Figs. 14 to 16, alternative means is shown for adjusting the angular position of the shuttle about its longitudinal axis, as well as alternative means for establishing electrical connection of an electrically operated gyro mechanism with a source of electric current when the shuttle is within the shuttle box. According to this embodiment, the shuttle construction may be as above described, including the tubular body por-

tion 79. However, the shuttle cap on the enlarged portion 141 thereof is provided with a polygonal periphery, which in the drawings is shown as square, the corners being rounded. The end 142 of the shuttle cap preferably is shaped so as to be of circular cross-sectional periphery so that it may be provided with the annular groove 64 having the functions hereinabove described. The interior of the shuttle box 143 is shaped similarly to the periphery of enlarged portion 141 of the shuttle cap and fits thereabout so as to permit longitudinal movement of the shuttle therein. In Figs. 14 to 17, the cross section of the interior of the shuttle box is shown as square. The outwardly flared funnel-shaped end 144 of the shuttle box is of the same internal cross-sectional shape, although enlarged, and, as shown in Figs. 16 and 17, can accommodate the enlarged portion 141 of the shuttle cap even when the angular disposition of the shuttle about its longitudinal axis relatively to the shuttle box is displaced to the relatively exaggerated position shown in these figures. It is apparent that when the shuttle is being received by the shuttle box, the contact of the enlarged portion 141 of the shuttle cap with the interior of the funnel-shaped end of the shuttle box will exert force tending to rotate the shuttle so that as the shuttle continues to enter the shuttle box the enlarged end of the shuttle cap will be brought into registration with the inner walls of the shuttle box and so that any angular displacement of the shuttle relative to the shuttle box will have been corrected before the shuttle comes to rest in the shuttle box. When this embodiment is employed, it is contemplated that the shuttle caps at each end of the shuttle be similarly shaped and that both of the oppositely-disposed shuttle boxes be formed as above described. While any angular displacement of the shuttle relatively to the shuttle box can be corrected by the means described above in connection with Figs. 14 to 17, such means involves impact of the shuttle with the inner wall of the shuttle boxes in order to make the desired correction, and for this reason it is preferred to provide means for making such correction after the shuttle has been brought to rest in the shuttle box, e. g., as described above in connection with Figs. 1 to 11.

The shuttle cap at one or both ends of the shuttle shown in Figs. 14 to 17 may encase a gyro mechanism that is electrically operated and which may be essentially the same as that shown in Fig. 13 except that the connections for the motor are taken to the strips 145 which lie substantially flush with one of the faces of the polygonal exterior of the enlarged portion 141 of the shuttle cap. The interior of the shuttle box is provided with conductor rails 146 which extend longitudinally of the shuttle box and are carried by an insulating member 147 that is secured to the shuttle box, the rails 146 being disposed so as to provide sliding contact with the strips 145 respectively, as shown in Fig. 14, when the shuttle enters the shuttle box. The rails 146 are connected to lines 148 respectively which are connected to any suitable source of electrical current. It is apparent that by the construction described electrical current can be connected to the electrically operated gyro mechanism within the shuttle substantially in advance of the ultimate position of the shuttle when it comes to rest within the shuttle box and after the shuttle has started its movement out of the shuttle box, as well as when the shuttle is at rest, thereby prolonging the interval

during which electrical power can be supplied to the gyro mechanism. The period during which contact is thus maintained will depend upon the length of the rails 146 along the longitudinal extent of the shuttle box.

Although the vertical movement imparted to the shuttle boxes for compensating for gravitational fall of the shuttle in free flight, as described above particularly in connection with Fig. 12, is preferable, it is not essential, as pointed out above. Thus, by appropriately selecting the contour of the cam 28 which controls the elevation and lowering of the shuttle boxes, each of the shuttle boxes can be caused to be stationary at its uppermost position of elevation for propulsion of the shuttle therefrom and so as to be stationary at its lowermost position for reception of the shuttle thereby, the difference between the uppermost and lowermost positions of elevation being the distance of gravitational fall of the shuttle in its free flight between the shuttle boxes. Alternatively, in order to compensate for the gravitational fall of the shuttle, one end only of each of the shuttle boxes can be elevated and lowered by the mechanism such as above described for causing the shuttle boxes to be elevated and lowered, in order that during propulsion of the shuttle the shuttle box axis will be uptilted toward the shed and will be tilted downwardly for reception of the shuttle. Moreover, the shuttle boxes may be fixed in stationary position but with their axes uptilted toward the shed so as to compensate for the gravitational fall of the shuttle.

Because of the high speeds contemplated for looms embodying my invention, it is desirable to stop the picking motion automatically by blocking the arms 43 by means of part 151 each time the bobbin is changed. Such stoppage would greatly lengthen the time interval for changing bobbins without incurring a production loss exceeding a fraction of one percent.

While certain specific embodiments and applications of this invention have been described hereinabove and shown in the accompanying drawings, it is to be understood that this has been done merely by way of illustration for the purpose of affording a clearer understanding of the invention and that this invention and its applications may be varied as the requirements of particular installations may indicate to be desirable without departing from the scope of this invention as defined by the following claims.

I claim:

1. Shuttle mechanism for looms comprising a shuttle, oppositely disposed spaced shuttle boxes each having an open end to receive said shuttle, a shuttle propelling member movable within each of said shuttle boxes for longitudinal reciprocation therein, actuating means for moving said members for acceleration and deceleration in each direction of the reciprocatory travel of each synchronously in opposite directions, releasable securing means carried by each of said members for contact with said shuttle, an engageable member presented adjacent each end of said shuttle adapted to be engaged by said securing means, actuating means for releasing said securing means during the shuttle propelling stroke of each of said shuttle propelling members, a gyro mechanism including a rotatable inertia member within said shuttle, impelling means for impelling said rotatable inertia member to effect rapid rotation thereof when said shuttle is within at least one of said shuttle boxes, positioning

means for adjusting the angular position of said shuttle about its longitudinal axis to predetermined position relative to the said shuttle box within which said rotatable member is impelled by said impelling means, and elevation changing means adapted to elevate each of said shuttle boxes in synchronism during the shuttle propelling stroke of said shuttle propelling members and to lower each of said shuttle boxes in synchronism during the return stroke of said members, said elevation changing means being adapted to impart an upward vertical component to the motion of said shuttle as it leaves each of said shuttle boxes and to cause the vertical velocity of the shuttle boxes at the moment of initial contact of the shuttle therewith at the end of each flight of the shuttle to be substantially the same as the vertical velocity of the shuttle, said actuating means for moving said shuttle propelling members being arranged for moving said members at approximately the rate of travel of said shuttle at the moment of initial contact therewith when said shuttle is received by said shuttle boxes, and said actuating means including resilient means coacting therewith to impart shuttle propelling motion to said shuttle propelling members and to receive the kinetic energy of said shuttle during the shuttle receiving motion of said members.

2. Shuttle mechanism for looms comprising a shuttle, a first shuttle box, a first shuttle propelling member movable within said shuttle box for longitudinal reciprocation therein, first actuating means for moving said member for acceleration and deceleration in each direction of its reciprocatory travel, a second shuttle box, a second shuttle propelling member movable within said second shuttle box for longitudinal reciprocation therein, second actuating means for moving said second shuttle propelling member for acceleration and deceleration in each direction of its reciprocatory travel, said first and second shuttle boxes being disposed for flight of said shuttle therebetween, synchronizing means associated with said first and second actuating means for causing said shuttle to effect initial contact of said shuttle alternately with said first and second shuttle propelling members while said members are moving at approximately the same velocity as said shuttle, a gyro mechanism within said shuttle, and actuating means for actuating said gyro mechanism when said shuttle is within at least one of said shuttle boxes.

3. Shuttle mechanism for looms comprising a shuttle including a casing member and gyro mechanism within said casing member, a horizontally disposed shuttle box having an open end to receive said shuttle, means for supplying power to actuate said gyro mechanism by communication through and between said shuttle box and said casing member when said shuttle is within said shuttle box in predetermined angular position about its longitudinal axis relative to said shuttle box, and means for adjusting said shuttle angularly about its longitudinal axis while within said shuttle box to cause it to assume said predetermined angular position about its longitudinal axis relative to said shuttle box.

4. Shuttle mechanism for looms comprising a shuttle, a shuttle box having an open end to receive said shuttle, and means for rotating said shuttle about its longitudinal axis to predetermined position relative to said shuttle box while said shuttle is in its normal position of rest rela-

tive to the longitudinal extent of said shuttle box.

5. Shuttle mechanism for looms according to claim 4 wherein said means for adjusting the angular position of said shuttle within said shuttle box includes a tapered slot extending longitudinally of the shuttle on the periphery thereof, a movable part carried by said shuttle box adapted to be moved into said tapered slot, and means for moving said movable part relative to said tapered slot when said shuttle is in its normal rest position in said shuttle box to effect angular adjustment of said shuttle about its longitudinal axis.

6. Shuttle mechanism for looms comprising a shuttle including a casing member and gyro mechanism within said casing member, a horizontally disposed shuttle box having an open end to receive said shuttle, a shuttle propelling member movable within said shuttle box for longitudinal reciprocation therein, actuating means for moving said shuttle propelling member for acceleration and deceleration in each direction of its reciprocatory travel, releasable securing means carried by said shuttle propelling member, an engageable member presented by said shuttle adapted to be engaged by said securing means, said engageable member and said securing means being adapted for rotary adjustment of said shuttle about its longitudinal axis relative to said shuttle propelling member when said engageable member and said securing means are in engagement, means for supplying power to actuate said gyro mechanism by communication through and between said shuttle box and said casing member when said shuttle is within said shuttle box in predetermined angular position about its longitudinal axis relative to said shuttle box and while said securing means and said engageable member are in engagement, and means for adjusting said shuttle angularly about its longitudinal axis while said shuttle is within said shuttle box with said securing means and said engageable member in engagement to cause said shuttle to assume said predetermined angular position about its longitudinal axis.

7. Shuttle mechanism for looms comprising a shuttle, a gyro mechanism within said shuttle including an inertia member rotatable about an axis disposed longitudinally of the shuttle, a shuttle box adapted to receive said shuttle, and means for supplying actuating power to said gyro mechanism when said shuttle is within said shuttle box.

8. Shuttle mechanism for looms comprising a shuttle having a casing member, a gyro mechanism within said casing member including a rotatably mounted inertia member having deflectors associated therewith for causing rotation of said inertia member, aperture means in said casing member, a shuttle box, and aperture means in said shuttle box, said aperture means in said casing and said aperture means in said shuttle box being disposed for directing a jet of air therethrough to impinge upon said deflectors when said shuttle is within said shuttle box to cause rotation of said rotatable inertia member of said gyro mechanism.

9. Shuttle mechanism for looms comprising a shuttle having a casing member, a gyro mechanism within said casing member including a rotatably mounted inertia member, electric motor means for causing rotation of said inertia member, and electrical circuit means adapted to actuate said motor means to rotate said inertia

member when said shuttle is within said shuttle box.

10. A loom shuttle comprising a casing member and a gyro mechanism within said casing member for stabilizing said shuttle in its flight, said gyro mechanism including a rotatably mounted inertia member presenting a plurality of deflectors, and said casing member being provided with aperture means disposed for directing an air jet therethrough for impinging on said deflectors to cause rotation of said rotatable inertia member of said gyro mechanism.

11. A loom shuttle comprising a casing member and a gyro mechanism within said casing member for stabilizing said shuttle in its flight, said gyro mechanism including a rotatably mounted inertia member and electric motor means for causing rotation of said inertia member, and said motor means including circuit means containing contact members presented exteriorly of said casing.

12. Shuttle mechanism for looms for effecting reciprocatory motion of a shuttle through the shed of a loom, said mechanism comprising a shuttle, a first longitudinally stationary shuttle box, a first shuttle propelling member movable longitudinally within said shuttle box and adapted to abut against one end of said shuttle, first actuating means for reciprocating said shuttle propelling member within said shuttle box in one direction to propel said shuttle for ejection from said shuttle box and in the opposite direction to return said shuttle propelling member to its original position, a second longitudinally stationary shuttle box, a second shuttle propelling member movable longitudinally within said second shuttle box and adapted to abut against the opposite end of said shuttle, second actuating means for reciprocating said second shuttle propelling member within said second shuttle box in one direction to propel said shuttle for ejection from said second shuttle box and in the opposite direction to return said second shuttle propelling member to its original position, said first and second shuttle boxes being disposed adjacent and outside the shed of the loom for reciprocatory travel of the shuttle therebetween, and said first and second actuating means being adapted to impart to said first and second shuttle propelling members motions having maximum velocities which are substantially equal for each of said members and for each of the directions of travel of said respective members, said maximum velocities being reached at points in the strokes of said shuttle propelling members that are spaced apart by a distance substantially equal to the product of said maximum velocity and the time interval between a moment of maximum velocity of the impelling stroke of one of said shuttle propelling members and a succeeding moment of maximum velocity of the other of said shuttle propelling members in its shuttle receiving stroke, whereby said shuttle is propelled back and forth from one of said longitudinally stationary shuttle boxes for reception in the other with the initial contact of said shuttle with the receiving shuttle propelling member occurring when said shuttle and said receiving member are moving in the same direction substantially at said maximum velocity.

13. Shuttle mechanism according to claim 12 wherein resilient means coacts with said first and second actuating means to impart shuttle propelling motion to said first and second shuttle propelling members respectively for ejection of

said shuttle from said first and second shuttle boxes respectively and to receive and conserve the kinetic energy of said shuttle in being brought to rest in said first and second shuttle boxes respectively during the shuttle receiving motion of said first and second shuttle propelling members respectively and wherein said first and second actuating means include cam means adapted to control the timing and rate of actuation of said shuttle propelling members in each direction of the travel thereof.

14. Shuttle mechanism for looms comprising a movable shuttle propelling member, actuating means for moving said shuttle propelling member in one direction to propel a shuttle for flight from said member and for returning said member to its original position, and means for causing return flight of the shuttle to said member, said actuating means including resilient means provided by gaseous fluid under compression which coacts therewith to move said member during its shuttle propelling stroke and to receive and conserve the kinetic energy of the shuttle on completing its return flight toward said member and including cam means adapted to control the timing and rate of travel of said member during its shuttle propelling stroke and to control the return of said member to its original position following its shuttle propelling stroke.

15. Shuttle mechanism for looms comprising a horizontally disposed shuttle box having an open end to receive a shuttle, a movable shuttle propelling member, actuating means for moving said member to propel a shuttle from said shuttle box toward the shed of a loom and means for imparting an upward movement to said shuttle box during the shuttle propelling movement of said shuttle propelling member to impart an upward component of movement to said shuttle when propelled from said shuttle box.

16. Shuttle mechanism for looms comprising a movable shuttle propelling member adapted to propel a shuttle toward the shed of a loom, an oppositely disposed shuttle box spaced from said member and adapted to receive the shuttle so propelled and means for causing said shuttle box to have a downward velocity approximately equal to the gravitational downward component of the velocity of said shuttle at the end of its flight at the moment of initial contact of said shuttle with said shuttle box.

17. Shuttle mechanism for looms comprising a shuttle, a first horizontal shuttle box, a second horizontal shuttle box spaced from said first shuttle box, means for propelling said shuttle from each of said shuttle boxes toward the other, means for imparting vertical reciprocatory motion to said shuttle boxes, and synchronizing means for causing said shuttle boxes to be in upward movement during propulsion of said shuttle therefrom and to be in downward movement during reception of said shuttle by said shuttle boxes at a rate that is approximately the rate of gravitational fall of said shuttle at the end of the period of flight of said shuttle between said shuttle boxes.

18. Shuttle mechanism for looms comprising a shuttle, a horizontally disposed shuttle box having an open end to receive said shuttle, a shuttle propelling member movable within said shuttle box for longitudinal reciprocation therein, actuating means for moving said shuttle propelling member for propulsion of said shuttle out of said shuttle box, releasable securing means carried by said shuttle propelling member, an engageable

member presented by said shuttle adapted to be engaged by said securing means for maintaining said shuttle secured against longitudinal movement relative to said shuttle propelling member, and means for releasing said securing means during the shuttle propelling motion of said shuttle propelling member to release said shuttle from said securing means, said securing means carried by said shuttle propelling member and said engageable member presented by said shuttle for engagement with said securing means being relatively rotatable so that the angular position of rotation of said shuttle about its longitudinal axis may be adjusted when said engageable member presented by said shuttle is engaged by said securing means.

19. Shuttle mechanism for looms comprising a shuttle, a horizontally disposed shuttle box having an open end to receive said shuttle, a shuttle propelling member movable within said shuttle box for longitudinal reciprocation therein, actuating means for moving said shuttle propelling member for propulsion of said shuttle out of said shuttle box, releasable securing means carried by said shuttle propelling member, an engageable member presented by said shuttle adapted to be engaged by said securing means for maintaining said shuttle secured against longitudinal movement relative to said shuttle propelling member, means for releasing said securing means during the shuttle propelling motion of said shuttle propelling member to release said shuttle from said securing means, a movable part and means which coacts with said means for releasing said securing means and which is adapted to prevent release of said shuttle from said securing means responsive to movement of said movable part so that said shuttle can be prevented from leaving said shuttle box.

20. Shuttle mechanism for looms comprising a shuttle, a horizontally disposed shuttle box having an open end to receive said shuttle, a shuttle propelling member movable within said shuttle box for longitudinal reciprocation therein, means for moving said shuttle propelling member for acceleration and deceleration in each direction of its reciprocatory travel, an engageable member presented by said shuttle, releasable securing means carried by said shuttle propelling member at the end thereof toward said shuttle, and actuating means for said releasable securing means, said actuating means including a movable part carried by said shuttle propelling member, movement of which in one direction causes said securing means to be released and movement of which in the opposite direction causes said securing means to be in position for engaging said engageable member presented by said shuttle, a part carried by said shuttle box arranged to coact with said movable part to move said movable part for release of said securing means during the shuttle propelling stroke of said shuttle propelling member and to move said movable part during the shuttle receiving stroke of said shuttle propelling member to restore said securing means to position for engaging said engageable member presented by said shuttle, and means for moving said part carried by said shuttle box out of operative position for coacting with said movable part carried by said shuttle propelling member so that said actuating means for releasing said securing means may be rendered inoperative to release said shuttle from said securing means.

21. Shuttle mechanism for looms comprising a

31

shuttle, oppositely disposed shuttle boxes, means for propelling said shuttle for free flight in reciprocatory motion between said shuttle boxes, a gyro-mechanism within said shuttle for stabilizing the shuttle in its flight, and means for actuating said gyro-mechanism.

22. Shuttle mechanism for looms comprising a first shuttle box, a second oppositely disposed shuttle box spaced from said first shuttle box, propelling means for propelling said shuttle from each of said shuttle boxes for free flight toward the other, means for imparting vertical reciprocatory motion to said shuttle boxes, and synchronizing means co-acting with said propelling means and with said means for imparting vertical reciprocatory motion to said shuttle boxes and adapted to effect substantial alignment of the leading end of the shuttle with each of said shuttle boxes at the end of the free flight of the shuttle in each direction between said shuttle boxes.

23. Shuttle mechanism for looms comprising a movable shuttle propelling member, actuating means for effecting reciprocatory motion of said shuttle propelling member in one direction to propel a shuttle for flight from said member and in the opposite direction for returning said member to its original position, means for causing return flight of the shuttle to said member, and synchronizing means which is associated with said actuating means and with said means for causing return flight of the shuttle and which is adapted to cause said shuttle propelling member to be in motion in the direction of motion of the shuttle on its return flight at the moment of initial contact of said shuttle with said member, said actuating means being adapted to effect deceleration of said shuttle propelling member and said shuttle in contact therewith to position of rest after initial contact of said shuttle with said member and to receive the kinetic energy of the shuttle on completing its said return flight toward said member for utilization in supplying the energy for maintaining the reciprocatory motion of said shuttle propelling member.

24. The combination with a shuttle mechanism for looms comprising a shuttle, a shuttle box and means for propelling said shuttle from said shuttle box toward the shed, a gyro-mechanism within said shuttle arranged to oppose yaw of said shuttle during its flight in all directions from the longitudinal axis of said shuttle and means for actuating said gyro-mechanism.

25. Shuttle mechanism for looms comprising a movable shuttle propelling member, actuating means for moving said shuttle propelling member in one direction to propel a shuttle for flight from said member and for returning said shuttle

32

propelling member to its original position, and corresponding means for causing the return flight of the shuttle to said member, said actuating means including resilient means coacting therewith to move said member during its shuttle propelling stroke and including power operated cam means adapted to control the acceleration, deceleration, timing and maximum rate of travel of said member during its shuttle propelling stroke and to control and effect the acceleration, deceleration, timing and maximum rate of travel of said member during its return to its original position following the shuttle propelling stroke for initially receiving the shuttle on its return flight thereagainst when said member is moving substantially at its maximum rate of travel on the return stroke of said member, said maximum rate of travel on the return stroke of said member being substantially the same as the maximum rate of travel of said member on its shuttle propelling stroke, whereby said shuttle is received by said member while said shuttle and said member are traveling at substantially the same velocity and whereby the kinetic energy of the shuttle on its return flight is received and conserved by said resilient means for release on the next succeeding shuttle propelling stroke of said member under the influence of said resilient means.
